UNITED STATES PATENT OFFICE

WILLIS O. PROUTY, OF HERMOSA BEACH, CALIFORNIA, ASSIGNOR, BY MESNE ASSIGNMENTS, TO METLOX CORPORATION, LTD., OF MANHATTAN BEACH, CALIFORNIA, A CORPORATION OF CALIFORNIA

LUMINOUS TUBE

Application filed October 31, 1928. Serial No. 316,158.

This invention relates to luminous tubes, and especially to tubes made from translucent material, such as glass, that have an ionizable gas filling therein, capable of luminescence when excited by electrical energy.

Ordinarily, such tubes have a filling of a "noble" monatomic gas, such as helium, argon or neon, or mixtures thereof; but my invention applies as well to tubes utilizing other gases or combination of gases. Such tubes usually have an internal gas pressure of about 6 m. m. of mercury. The luminescence is secured by impressing a sufficient potential difference across the column of gas in the tube. The current flow through the tube of the known types is maintained at a low value. It has been found that attempts to increase the luminosity by increasing the current flow are not very satisfactory. The electrodes that are utilized for impressing the potential are too greatly heated.

It is one of the objects of my invention to make it possible to pass a high current through the tube, and thereby to multiply greatly the light emitted thereby.

Such excessive or large energization has other very useful effects, besides an increase in luminosity. By using a blue tube (that is, one employing a mixture of a rare monatomic gas and mercury vapor), the increased luminescence also causes greater volume of ultra violet radiations. This is useful for its actinic value, as for photography under artificial light; as well as for its therapeutic value, as in the treatment of rachitic conditions.

In order to obtain these beneficial results, I arrange the tube in such a way that it can be excited by the aid of a plurality of independent pairs of electrodes, each energized by a source distinct from the others. In this way, I find it a simple matter to keep the electrodes cool. In the preferred form of my invention, the capability of the electrodes to radiate heat is enhanced by making them of the external type; that is, they form a tubular extension or cap to the translucent tube, and have a surface external of the tube that can efficiently radiate heat, while its internal surface acts as the active electrode surface.

Accordingly, it is another object of my invention to provide a series of electrodes at each end of the tube, whereby the problem of cooling is rendered simple even for large current flow; and whereby it is easy to control the degree of energization, as by varying the number of pairs of active electrodes.

It is another object of my invention to make it possible to blend rays of different or complementary colors to secure a daylight effect, and especially by individual control of the degree of luminescence of the constituent tubes.

My invention possesses many other advantages, and has other objects which may be made more easily apparent from a consideration of several embodiments of my invention. For this purpose I have shown a few forms in the drawings accompanying and forming part of the present specification. I shall now proceed to describe these forms in detail, which illustrates the general principles of my invention; but it is to be understood that this detailed description is not to be taken in a limiting sense, since the scope of my invention is best defined by the appended claims.

Referring to the drawings:

Figure 1 is a view, mainly diagrammatic, of a luminous system embodying my invention;

Fig. 2 is an enlarged fragmentary view showing the structure of the preferred form of electrode utilized in my invention;

Fig. 3 shows a modified form of the system shown in Fig. 1;

Fig. 4 is an enlarged fragmentary view of an alternative form of electrode.

Fig. 5 is a plan view, partly broken away, of an illuminating device arranged to produce substantially white light; and

Fig. 6 is a section along plane 6-6 of Fig. 5.

I show in Fig. 1, a tube 11 of indefinite length, which can be made from glass or other translucent material. This tube can be made of any desired length, and it can be convoluted in any desired manner. For a concentrated source, the tube can be coiled compactly, as indicated in the modification of 100

Fig. 3, where tube 12 is shown as spiralled to form a source of intense illumination.

The tube 11 is arranged at each end with a plurality of branches, such as 13, 14, 15, at 5 one end; and 16, 17, 18 at the other end. These branches all lead into the main tube 11, and there are as many branches at one end as the other. In the present instance only three branches are shown, but obviously, any de- 10 sired larger number can be used. These branches are made long enough to accommodate the electrodes, such as 19, 20, 21, 22, 23, 24.

Before explaining the tube structure in 15 further detail, I shall point out the advantages of the device as thus far set forth. Each of the plurality of parallel electrodes, operates to lead its quota of current to the gaseous filling in the tube 11. Accordingly, 20 each needs to carry but a fraction of the total current, and the electrode is not overloaded. Furthermore, since the greatest heating effect occurs at the active electrode surface (where the gas molecules make contact with the elec- 25 trode), the spatial separation of the branches 13, 14, 15, and of the branches 16, 17, 18, in which are incorporated these active surfaces, assists in conducting heat away from these surfaces. Convection currents of air 30 can more effectively cool the exterior surfaces of these ends 13 to 18. If the plurality of electrodes at each end would be combined to form a single equivalent electrode, the amount of exposed surface would be con- 35 siderably reduced, and undue heating would result.

This cooling effect is of prime importance. It is secured by separating the total electrode 40 surface into a plurality of parts. But the effect is markedly enhanced by the use of the particular form of electrode, one of which is shown in greater detail in Fig. 2. In this figure, the electrode 19 is shown as a hollow metal cap, inserted over the open end of its 45 tube branch 13, and sealed in an air tight manner therein. This leaves a large exposed metallic surface, directly in thermal conductive relation to that portion of the structure which develops the heat.

50 Of course, internal electrodes could also be used, such as shown in Fig. 4 for example. In this form, metal tube 32 serves as an electrode, and is sealed in the enlarged end 33 of the corresponding branch 34. A lead or 55 support 35 is sealed into squash 36 to support and conduct current to electrode 32. A glass ring 37 can also be provided if desired, at the free end of the electrode to assist in maintaining clearance between the electrode and the 60 tube.

The manner in which the pairs of electrodes can be excited is diagrammatically illustrated in Fig. 1. Electrodes 19 and 22 are connected across the high potential side 65 of a step-up transformer 25. This trans-

former is energized through a control switch 26 from the ordinary commercial mains 27. Similarly, electrodes 20 and 23 are connected across the high potential side of a step-up 70 transformer 28, energized through switch 29 from mains 27; and electrodes 21 and 24 are connected across the high potential side of a step-up transformer 30 through switch 31 from mains 27.

Care must be taken to ensure that the polarities of all electrodes at each end of the tube are the same. The branches 13, 14, 15 and 16, 17, 18 help to keep the transformers insulated from one another, and to keep them properly operating in parallel, for any short circuiting current, say between electrodes 19 and 20, must find its way through the two branches 13 and 14.

The degree of luminescence can obviously be varied by operation of switches 26, 29, and 85 31, whereby any one or more of the transformers can be rendered active, while the rest are left inactive. Thus for ordinary illumination, one transformer alone can be used; for higher degrees of illumination, additional transformers can be energized in succession. This capability of varying the degree of luminescence is of considerable importance in therapeutic and photographic work.

The division of the active electrode surface into a number of parts makes it possible to energize the tube 11 to an intense degree without dangerous heating or sputtering. The intense illumination that results therefrom 100 is maintainable indefinitely. Furthermore, there is no danger that any hot spots will develop on the active electrode surfaces, which hot spots have been noted to occur rather frequently in electrodes that are overloaded. These hot spots are due to the preference sometimes exhibited by the current to concentrate at a definite locality on the electrode. With multiple electrodes, this danger of a concentrated discharge seems very ma- 110 terially lessened.

Due to the fact that I can vary the degree of luminescence in a simple manner, it is possible accurately to blend rays of complementary colors to secure substantially white light. 115 For this purpose, an arrangement such as illustrated in Figs. 5 and 6 can be used. A box 38 having a curved reflector 39 in front serves as a support for all the tube parts. In front of the reflector are supported in any 120 appropriate manner, a plurality of luminous tubes of different or complementary colors, at least one of said tubes being constructed and controlled as in Fig. 1.

Thus for example, a convoluted tube 41 is 125 shown, of indefinite length, having a plurality of electrode extensions 42 at one end; and extensions 43 at the other end. These can be bent to extend downwardly through apertures 40 in reflector 39. The controlling and 130

energizing devices, as illustrated in Fig. 1, can be located in box 38 back of reflector 39, or in any other convenient location.

This tube 41 can be caused to emit a blue light, as by providing it with a filling of argon or neon with a few drops of mercury. Its intensity can be regulated by the control mechanism. In order to secure white illumination, I provide another tube 44 arranged between a pair of convolutions of tube 41 and emitting a complementary color, such as red. This tube also has extensions, such as 45, that project back of reflector 39 through apertures 46.

By appropriate manipulation of switches 26, 29, 31, the intensity of illumination of tube 41 can be controlled, so that the correct amount of blue light is provided for forming white illumination, and to complement the light emitted by tube 44. Such an arrangement is of considerable value for motion picture photography; and especially when pictures are made with sound recordings, since the tubes are silent in operation.

25 I claim:

1. In a device of the character described, a tube having a plurality of branches at each end, an electrode associated with each of the branches, and means for separately impressing a potential difference across separate pairs of electrodes, each pair including an electrode respectively at each end of the tube.

2. In a device of the character described, a tube having a plurality of electrodes at each end, and having a gaseous filling capable of ionization, and means for separately impressing a potential difference across separate pairs of electrodes, each pair including an electrode respectively at each end of the tube.

3. The combination as set forth in claim 2, with the addition of separately controllable means for energizing each pair of electrodes.

4. In a device of the character described, a tube having a plurality of branches at each end, an electrode of the exterior type located at the end of each branch and having an internal active surface, and means for separately impressing a potential difference across separate pairs of electrodes, each pair including an electrode respectively at each end of the tube.

5. In a device of the character described, a tube having a plurality of electrodes of the external type at each end, and having a gaseous filling capable of ionization, and means for separately impressing a potential difference across separate pairs of electrodes, each pair including an electrode respectively at each end of the tube.

6. The combination as set forth in claim 5, with the addition of separately controllable means for energizing each pair of electrodes.

7. In a device capable of use for providing intense illumination for therapeutic or photo-

graphic purposes, a tube having a gaseous filling in which there is included a monatomic gas of the noble group, and means for intensely energizing said gaseous filling, including a series of electrodes at each end of the tube, and means for selectively energizing said electrodes in pairs across the tube.

8. In a device capable of use for providing intense illumination for therapeutic or photographic purposes, a tube having a gaseous filling in which there is included a monatomic gas of the noble group, and means for intensely energizing said gaseous filling, including a series of electrodes of the external type at each end of the tube, and means for selectively energizing said electrodes in pairs across the tube.

9. In a device capable of use for providing intense illumination for therapeutic or photographic purposes, a tube having a gaseous filling in which there is included a monatomic gas of the noble group, and means for intensely energizing said gaseous filling, including a plurality of branches for the tube at each end thereof, an electrode associated with each branch, and means for separately energizing separate pairs of electrodes, each pair including an electrode respectively at each end of the tube.

10. In a device capable of use for providing intense illumination for therapeutic or photographic purposes, a tube having a gaseous filling in which there is included a monatomic gas of the noble group, and means for intensely energizing said gaseous filling, including a plurality of branches for the tube at each end thereof, an electrode of the external type, associated with each branch, and means for separately energizing separate pairs of electrodes, each pair including an electrode respectively at each end of the tube.

11. In a device of the character described, a plurality of luminous tubes, one of said tubes having a plurality of pairs of electrodes, the electrodes in each pair being at opposite ends of the tube, separate means for exciting both tubes, and means whereby the number of pairs of electrodes that are active in the said one of the tube can be controlled.

In testimony whereof I have hereunto set my hand.

WILLIS O. PROUTY.
